CLAIM

The ornamental design for a globe for roadway luminaire, as shown and described.

DESCRIPTION

FIG. 1 is a bottom, rear perspective view of a globe for roadway luminaire showing our new design;

FIG. 2 is a bottom plan view thereof;

FIG. 3 is a side elevational view thereof;

FIG. 4 is a front elevational view thereof;

FIG. 5 is a rear elevational view thereof.

The luminaire housing is shown in broken lines in FIG. 1 for illustrative purposes only.
